UNITED STATES PATENT OFFICE.

HENRY F. LOEWER, OF ROCHESTER, NEW YORK.

MACHINE FOR TRIMMING LAST-HEELS.

1,072,963.

Specification of Letters Patent. Patented Sept. 9, 1913.

Application filed August 21, 1912. Serial No. 716,314.

To all whom it may concern:

Be it known that I, HENRY F. LOEWER, a citizen of the United States, and resident of Rochester, in the county of Monroe and 5 State of New York, have invented certain new and useful Improvements in Machines for Trimming Last-Heels, of which the following is a specification.

This invention relates to a machine 10 adapted to remove or trim off, from the heel of a partially completed last, the surplus material left at this point by the last-lathe.

In a Patent, No. 916,569, granted to me 15 March 30, 1909, I have described a machine of the kind in question in which the last is held in operative relation with a rotary trimming-cutter by means of a last-support or jack, the jack having certain movements 20 imparted to it manually by which the last is moved relatively to the cutter in such a manner as to cause the cutter to trim the contour of the last-heel from top to bottom, and to produce a predetermined outline.

25 The present invention relates particularly to improvements in the machine disclosed in said patent, and one object of the invention is to relieve the operator of the labor of producing the tangential movements of the jack by which the point of operation is transferred from top to bottom of the last. To this end I employ power-actuated mechanism by which the necessary movements are imparted to the jack, this mechanism 30 acting, in the illustrated embodiment of the invention, to first raise the jack and then arrest this movement and automatically return the jack to its original position. This 35 cycle of operations is repeated automatically at each actuation of a treadle or other manually-operable device.

Another object of the invention is to provide for various adjustments of the machine by which it may be readily adapted for operation upon lasts of a great variety of sizes 45 and shapes, and to this end I employ various features of construction and arrangement of parts which will be hereinafter set forth in connection with the description of 50 the illustrated embodiment of the invention.

In the accompanying drawings:—Figure 1 is a front-elevation of a machine embodying the present invention; Fig. 2 is a plan-view of the machine of Fig. 1; Fig. 3 is a 55 side-elevation of the upper portion of the machine, looking from left to right in Fig.

1; Fig. 4 is a plan-view, on a larger scale, showing in detail a portion of the mechanism for operating the belt-shippers; Fig. 5 is a front-elevation, partly in section, of the parts shown in Fig. 4; Fig. 6 is a vertical section through the jack by which the last is supported; and Fig. 7 is a plan-view of the jack.

In the illustrated embodiment of the invention I employ, as in the machine of said patent, a rotary cutter 11 in the form of a saw of the "wabble" type, this saw being mounted on a shaft 12 journaled in bearings 13 on the frame of the machine. The 60 shaft and the saw are driven by pulleys and a belt 14 connecting them with a countershaft 15, which may be actuated from any suitable source of power. The last-jack is carried by a table 16 at the front of the 65 machine, and to this table are imparted the 70 vertical movements by which the jack and the last are moved tangentially with respect to the cutter. To this end the table is carried by a frame 17 and 18 which slide in bearings 19 on the 75 frame of the machine. A shaft 20, journaled upon the frame of the machine, is provided with two pinions 21 which mesh with rack-teeth cut in the back of the slide- 80 rods 17 and 18 (see Figs. 1 and 3), so that by rotation of the shaft 20 in opposite directions the table may be raised and lowered.

The shaft 20 is provided, at its right-hand end, with a gear 22, constituting one 85 element of a train of speed-reducing gearing, which terminates in a pinion 24 on a counter-shaft 25. The countershaft is journaled in the frame of the machine parallel with the shaft 20, and is provided with two 90 loose pulleys 26 and 27 between which is a fast pulley 28. Two belts 29 and 30 connect the pulleys just mentioned with any suitable source of power, these belts moving constantly, and the belt 29 being crossed so as 95 to move in the opposite direction from the belt 30. By this arrangement the fast pulley 28 and the shaft 25, and other parts connected therewith, may be driven in either direction, or the two belts may run freely 100 on the loose pulleys 26 and 27 without actuating the table-mechanism in either direction.

To control the positions of the belts 29 and 30 they are engaged, respectively, by 105 forked shipper-levers 31 and 32, as shown particularly in Figs. 1 and 2. These ship-

per-levers are pivotally mounted upon a bar 33 forming a part of the frame of the machine. Above the shipper-levers a slide-plate 35 is mounted to move horizontally through openings in upward projections 34 from the bar 33. This slide-plate is provided with a cam-slot comprising a straight central portion 36 and two inclined end-portions 37 and 38. The shipper-levers are provided with rollers 39 and 40 which engage this cam-slot, and in the intermediate position of the plate the rollers are at opposite ends of the straight portion 36, in which position the two belts are held upon the loose pulleys. When the plate is moved to its extreme left-hand position, as in Fig. 2, the belt 29 is brought into engagement with the fast pulley 28, while in the opposite extreme position of the plate the belt 30 is moved to the fast pulley, so that in these two extreme positions the mechanism may be actuated to raise and lower the table 16, respectively, while in the normal position of the machine the mechanism is inoperative, the two belts running freely on the loose pulleys.

The slide-plate 35 is actuated by means of a treadle 41 which is connected, by a link 42, with a bell-crank lever 43. The lever 43 is pivoted on a stud 44 on the frame of the machine, and its upper end engages a pin 45 on the plate 35. A spring 46 tends to raise the treadle, but the treadle normally occupies a neutral position midway between its uppermost and lowermost positions, being held at this point by means to be presently described. When it is desired to throw the machine into operation the treadle is depressed to its lowermost position, as shown in Fig. 1, and the slide-plate 35 is thus moved to the left, causing the belt 29 to drive the fast pulley and the countershaft 25. Through the gear-mechanism previously described the table 16 is then raised until it reaches a predetermined position.

To reverse the operation of the table-mechanism at the upper end of its movement, I employ mechanism shown particularly in Figs. 2, 4 and 5. The slide-plate 35 is provided with an opening engaged by a stud 47 which projects downwardly from the rear end of a lever 48, the lever being pivoted upon a bracket 49 forming part of the frame of the machine. The forward end of the lever is connected, by a rod 50, with an arm 51, and this arm is fixed on the upper end of a rock-shaft 52 journaled in the frame of the machine. Near its upper end the rock-shaft carries a dog 53 which is adapted to coöperate with a latch 54. This latch is carried by a spring-pressed slide 55 moving in a recess in the frame of the machine. The dog normally occupies a position in the rear of the latch, but when the slide-plate 35 is moved to the left, as above described, the rock-shaft and the dog are

rocked from left to right, thus causing the dog to engage the beveled extremity of the latch and move past the same and into the position of Fig. 4. If now the operator, after having depressed the treadle to produce this movement, releases the treadle, the dog is held, by the latch, against reverse rotation, and thus the slide-plate, the belt-shippers and the treadle-mechanism are all held against return movement, so that the rising movement of the table-mechanism continues automatically.

To release the dog 53 at the proper movement and permit the rising movement of the table to terminate, a trip 56 is fixed to the slide-rod 17, this trip having a beveled lug 57 which coöperates with a forward projection 58 on the latch 54. When the table has risen to the position of Fig. 1 the beveled surface of the lug 57 forces the projection 58 and the latch to the right, thus releasing the dog 53 and permitting the rock-shaft 52 to rotate. The spring 46 now acts to draw the treadle from its lowermost to its uppermost position, thus moving the slide-plate 35 to its farthest right-hand position. In the course of this movement the belt 29 is first moved from the fast pulley to the loose pulley 26, thus terminating the rising movement of the table, and the shipper 29 then shifts the belt 30 from the loose pulley 27 to the fast pulley 28, thus rotating the gearing in the opposite direction and causing the table to move downwardly again.

To terminate automatically the downward movement of the table a cam 59 is fixed to the lower part of the rock-shaft 52, this cam having an inclined surface adapted to coöperate with a roller 60 journaled on the trip 56. The adjustment of the parts is such that when the table reaches its predetermined lowermost or normal position the roller engages the cam and thus rotates the rock-shaft back to its normal position, thus moving the slide-plate 35 to neutral position, in which both of the belts are running upon the loose pulleys, and depressing the treadle from its uppermost position to its normal, central position. The parts are then held in this position, against the opposition of the spring 46, by the action of the cam 59 and the roller 60 until the treadle is again depressed to repeat the cycle of operations just described.

The jack by which the last is carried is shown particularly in Figs. 6 and 7. It comprises a slide 61, which has at the bottom a dovetailed projection fitting a corresponding slot extending fore-and-aft in the upper surface of the table 16, so that the jack as a whole may slide toward or from the trimming-cutter. The last is supported upon a bed 63 provided, near its rear end, with a heel-block 64 upon which the heel-portion of the last rests. The toe of the

last is engaged by a toe-gage 65. This toe-gage is adjustable along the bed, having a downward extension which moves in a longitudinal slot in the bed and which is engaged by an adjusting-screw 66 provided, at the front, with a handle 67 by means of which it may be rotated. By this arrangement the toe-gage may be adjusted according to the length of the last upon which the machine is to operate. As in the machine of said patent, the last is fixed in the jack by means of two heel-clamps 68 which engage the sides of the heel-portion of the last. These clamps are fixed on the upper ends of short rock-shafts 69 which are journaled in the bed 63. At their lower ends the shafts 69 carry arms 70, of which the forward extremities engage beveled surfaces on a cam-plate 71. This plate slides 20 against the bottom of the bed, being guided and supported by two screws 72 passing through slots in the cam-plate. The cam-plate is normally held in its rearmost position by means of two springs 74 connected with the cam-plate and with the bed, respectively, and these springs, through the sliding movement imparted by them to the cam-plate, act to force the arms 70 outwardly and thus force the heel-clamps 68 30 toward each other and into forcible engagement with the last.

To release the last from the action of the heel-clamps a hand-lever 75 is employed, this lever being pivoted, at one end, on the bracket 76 fixed to the bed 63. This lever is slotted to engage a stud 77 projecting downwardly from the cam-plate. The operator, by drawing the hand-lever forward, causes the cam-plate to move correspondingly and to release the arms 70, and these arms are then drawn toward each other by a spring 73 which connects them, thus moving the clamps away from each other and permitting the removal of the last therefrom.

45 A novel feature of the present machine resides in an arrangement by which the angular position of the bed may be varied in the plane of rotation of the trimming-cutter, to adapt the machine readily to lasts of different forms, and particularly to lasts in which the contour of the heel is more or less inclined. To this end the bed 63 is pivotally mounted at its rear end, having two arms 78 provided with hollow pivot-studs 79 loosely journaled in two brackets 80 fixed to the rear-end of the slide 61. The bed may thus be swung about the axis of the stud 79, thus adjusting its inclination with respect to the slide 61. To fix the bed in 50 its adjusted, angular position a plate 81 is fixed to one of the studs just outside of the left-hand bracket 80, as shown particularly in Figs. 3 and 6. This plate is slotted to receive a screw 82 by means of which the plate 55 may be clamped firmly against the outer

surface of the bracket. The screw 82 is provided with a handle by which it may be conveniently manipulated. For convenience in raising and lowering the forward end of the bed, in making the angular adjustment just described, a rack 83 is pivoted at its upper end to a lug on the bed, and this rack is free to move vertically in an opening 84 in the forward end of the slide 61. The forward surface of the rack 70 engages a bearing-roller 85, while the teeth on the rear surface of the rack are engaged by a pinion 86. This pinion is fixed on a shaft 87 journaled transversely on the slide 61, and a handle 88 is fixed to one end of the shaft, by which it may be conveniently rotated.

Another novel feature of the present invention resides in the means for locating the toe-gage 65 and other parts of the machine in adjusting the machine to operate upon a last of any given size or pattern. For this purpose I employ a device hereinafter described as a heel-gage, and consisting of a rod 89 which may be introduced through the hollow centers of the studs 79, as shown in Figs. 6 and 7. The rod 89 is recessed in such a manner as to receive the lower corner or angle of the last, where the contour of the heel joins the contour of the bottom, as shown in dotted lines in Fig. 6. In adjusting the machine, therefore, for any given last the rod 89 is introduced, being provided with a handle 90 by which it may be conveniently manipulated, and the last is then placed upon the bed and the heel-block, with the angle above mentioned seated in the recess in the heel-gage. The toe-gage 65 may then be adjusted by means of the handle 67 and the screw 66 until it 95 engages the forward extremity of the last, as shown in Fig. 1. The heel-gage may then be withdrawn so as not to interfere with the normal operation of the machine, and the parts are thereafter in position to 100 receive lasts similar to that for which they have been adjusted, it being necessary merely to open the heel-clamps, lay the last upon the bed and the heel-block, draw it forwardly into engagement with the toe-gage, and then clamp the last by means of the heel-clamps 68. By these operations the last will be brought accurately to the position in which the lower angle above referred to coincides with the pivotal axis about 115 which the bed is adjusted, as above described.

Another novel device employed in the present machine comprises a bar 94 herein-after referred to as the angle-gage. This bar is fixed in horizontal position on a slide 93 which slides vertically upon an upright rod 92 projecting from the right-hand bracket 80. In setting up the machine for any size or form of last the last is put into 120

- position by means of the heel-gage and the toe-gage as before described. The ankle-gage is then applied to the rod 92 and the bed is swung upwardly, or downwardly, as may be necessary, until the upper angle of the last, that is, the point where the heel joins the upper surface of the last, engages the lower front angle or edge of the angle-gage 94, as shown in dotted lines in Fig. 6. 5
- 10 In performing this adjustment the gage may be freely raised or lowered by movement of the slide 93 and the upright 92, according to the height of the last. When the bed has been adjusted as just described the last will 15 occupy a position in which the upper extremity of its heel-contour, terminating in what may be called the ankle-portion of the last, lies directly above the lower extremity or angle of the heel-contour, as shown in Fig. 6, this being the position in which the 20 guiding-mechanism of the machine is adapted to operate correctly to produce the required contour in the heel, and by adjusting the inclination of the bed in this manner the machine may be adapted to produce 25 similar contours upon the heel-portions of lasts in which the general inclination of the heel-contour may vary according to the style of last, and this may be done by the use of 30 a single pattern-plate and guide-wheel for all of such different styles.

In the machine of said patent I employed an adjustable pattern-plate and a guide-wheel, which coöperated to control the forward and rearward horizontal movements of the last-jack during the general tangential movement of the jack with respect to the trimming-cutter, whereby the desired contour was produced upon the heel of the 35 last. In the present machine I employ similar elements coöperating in substantially the same manner. The pattern-plate 95 is clamped upon the outer surface of the plate 81, being fixed in place by means of a clamping-plate 96 and a screw 97 provided with a 40 handle by which it may be conveniently manipulated. This pattern-plate is conveniently adjusted by the use of the heel-gage and the ankle-gage, the plate being moved 45 into simultaneous engagement with both of these members as shown in Fig. 3, and being 50 then clamped in this position.

The rear-edge of the pattern-plate 95 is formed to a contour corresponding in general character to the contour to which the last-heel is to be trimmed. This edge of the pattern-plate rests against the periphery of the guide-wheel 98, which is of generally circular form. The guide-wheel is loosely 55 journaled on a hub 99, which in turn is loosely journaled on a stud 100. This stud is fixed in an upright member 101 upon the frame of the machine, as shown particularly in Figs. 1 and 2.

60 As the pattern-plate is intended to co-

operate with certain specific portions of the periphery of the guide-wheel, means are provided for rotating the latter through a predetermined angle during the rising and falling movement of the last-jack and the pattern-plate. To this end the hub 99 forms 70 part of a segmental gear-wheel 102, which meshes with a rack 103 fixed to rise and fall with the table 16. An arm 104, fixed to the right-hand end of the hub 99, carries 75 a spring-pressed latch 105 which coöperates with one or another of a series of notches 106 in the edge of the guide-wheel, so that the wheel is caused to perform partial rotations together with the hub and the segmental gear as the table rises and falls. 80

The object of the latch just described is to permit different portions of the guide-wheel to coöperate with the pattern-plate, in the same manner and for the same purpose as in the machine described in said patent. The different segments 107, 108, 109, etc., of the periphery of the guide-wheel, while conforming approximately to the circular general form of the wheel, are curved 90 upon different radii, with the result that, while coöperating with the same pattern-plate, these different segments will produce heel-contours on the last of different degrees of convexity, and in this manner the 95 machine is adapted to operate upon lasts of similar pattern but different sizes without any adjustment of the machine other than the necessary change from one segment to another of the guide-wheel, and the corresponding adjustment of the toe-gage according to the lengths of the different sizes. 100

The general operation of the machine is as follows: The operator pulls the hand-lever 75 forwardly, thus at the same time opening the heel-clamps and moving the slide 61 forwardly upon the table. He then places the last upon the bed and moves it forwardly until the toe of the last is in engagement with the toe-gage. The operator 110 then presses the hand-lever rearwardly, thus causing the last to be clamped upon the jack, and at the same time forcing the slide rearwardly so as to bring the last into engagement with the trimming-cutter. At this 115 time the table is in its lowermost position, so that the cutter begins its operation at the ankle-portion of the last. The operator then depresses the treadle for a moment, whereupon the table begins to rise through the operation of the belt-shippers, as above described, and during this rising movement the heel of the last is trimmed from top to bottom. When the table and the jack reach their uppermost position the rising movement is automatically interrupted, as before described, and the table and jack then fall again to their normal lowermost position. The operator then pulls the hand-lever 75 forwardly again, thus releasing the last so that 120

it may be removed from the jack and a fresh last substituted.

The use of the hand-lever 75 for opening and closing the heel-clamps simplifies and facilitates the operation of the machine, since the movements of this lever, as just described, are in such directions as to perform the additional function of moving the slide and the jack toward and from the trimming-cutter, and by this arrangement, in connection with the automatic power-actuated mechanism for raising and lowering the jack, the machine is rendered very easy and rapid in operation and capable of being operated by unskilled labor.

My invention is not limited to the embodiment thereof hereinbefore described and illustrated in the accompanying drawings, but may be embodied in various other forms 20 within the nature of the invention as it is defined in the following claims.

I claim:—

1. A machine for trimming last-heels having, in combination, a rotary trimming-cutter, a jack for holding a last with its heel in engagement with the trimming-cutter, and means for moving the jack in a general direction tangential to the cutter, said means comprising a slide on which the jack is mounted, reversible gearing for actuating the slide in opposite directions, a manually-operable member for throwing the gearing into one operative position to move the slide in one direction, a detent for holding the gearing in said position, a trip carried by the slide and adapted to engage the detent and release the gearing from said position when the slide has completed its movement in said direction, resilient means for moving the gearing, when so released, to its opposite operative position, to impart a return movement to the slide, and means, actuated by the slide at the end of such return movement, to restore the gearing to neutral inoperative position.

2. A machine for trimming last-heels having, in combination, a rotary trimming-cutter, a jack for holding a last with its heel in engagement with the trimming-cutter, the jack comprising means for clamping the last laterally in place therein and being movable toward and from the cutter, means for positively arresting the movement of the jack toward the cutter, a manually-operable member connected with said clamping-means and operable, when moved in one direction, to cause the clamping-means to engage and clamp the last and the jack to move toward the cutter; and when moved in the opposite direction, to cause the jack to move away from the cutter and the clamping-means to release the last, and means for imparting a feeding movement to the jack in a general direction tangential to the cutter.

3. A machine for trimming last-heels having, in combination, a rotary trimming-cutter, a jack for holding a last with its heel in engagement with the trimming-cutter, the jack comprising clamping-means for 70 engaging the last laterally to clamp it in place therein and being movable as a whole toward and from the cutter, means for positively arresting the movement of the jack toward the trimming-cutter, a hand-lever 75 pivoted on the jack and movable thereon toward and from the cutter, and connections between the hand-lever and the clamping-means for causing the latter to close laterally upon the last when the hand-lever is 80 pushed toward the cutter.

4. A machine for trimming last-heels having, in combination, a rotary trimming-cutter, a jack for holding a last with its heel in engagement with the trimming cutter, 85 means for supporting the jack and for moving it in a general direction tangential with respect to the cutter, the jack being adjustable upon said means to vary the inclination at which the last is held in the plane of rotation of the cutter, and means for fixing the jack in adjustable position on said means.

5. A machine for trimming last-heels having, in combination, a rotary trimming-cutter, 95 a jack for holding a last with its heel in engagement with the trimming-cutter, the jack being movable toward the cutter to bring the last into operative engagement therewith, and a heel-gage adapted to be 100 engaged by the lower angle of the heel of the last in locating the last in the jack, the heel-gage being mounted movably upon the jack so that it may be removed, after use, from the path of operation of the cutter.

6. A machine for trimming last-heels having, in combination, a rotary trimming-cutter, a jack for holding a last with its heel in engagement with the trimming-cutter, the jack being movable toward the cutter to 110 bring the last into operative engagement therewith and being also adjustable to vary the inclination of the last in the plane of rotation of the cutter, and a gage adapted to register with the upper angle of the rear extremity of the last to assist in adjusting the angular position thereof, said gage being movably mounted upon the jack so that it may be removed, after use, from the path of operation of the cutter.

7. A machine for trimming last-heels having, in combination, a rotary trimming-cutter, a jack for holding a last with its heel in engagement with the trimming-cutter, the jack being movable toward the cutter to bring the last into operative engagement therewith, and being also adjustable to vary the inclination of the last in the plane of rotation of the cutter, and two gages adapted to register with the upper and 130

lower angles of the rear extremity of the last, respectively, to assist in adjusting the position thereof, said gages being movably mounted upon the jack so that they may be removed, after use, from the path of operation of the cutter.

8. A machine for trimming last-heels having, in combination, a rotary trimming-cutter, a jack for holding a last with its heel in engagement with the trimming-cutter, the jack being movable toward the cutter to bring the last into operative engagement therewith, and being also adjustable to vary the inclination of the last in the plane of rotation of the cutter, two gages adapted to register with the upper and lower angles of the rear extremity of the last, respectively, to assist in adjusting the position thereof, said gages being movably mounted upon the jack so that they may be removed, after use, from the path of operation of the cutter, a pattern-plate adjustably mounted on the jack and adapted to engage said gages to determine its operative position on the jack, and means co-operating with the pattern-plate to regulate the operative position of the jack during the trimming operation.

9. A machine for trimming last-heels having, in combination, a trimming-cutter rotative about a horizontal axis, a horizontal table movable vertically in front of the trimming-cutter, mechanism for imparting alternate rising and falling movements to said table, and a last-supporting jack comprising a slide carried by the table and movable toward and from the cutter, a bed carried by the slide and pivotally connected therewith at its rear end, said bed being angularly adjustable about its pivotal connection in the plane of rotation of the cutter, and means for clamping a last upon the bed.

10. A machine for trimming last-heels having, in combination, a rotary trimming-cutter, a jack for holding a last with its heel in engagement with the cutter, the jack comprising clamping-jaws mounted pivotally in position to swing against the sides of the last, a cam-plate slidable upon the jack, a hand-lever pivoted upon the jack and adapted to swing thereon toward and

from the cutter, the hand-lever being operatively connected with the cam-plate, and lever-arms connected with the clamping-jaws and engaging the cam-plate, whereby the jaws are caused to engage and clamp the last when the hand-lever is moved toward the trimming-cutter.

11. A machine for trimming last-heels having, in combination, a trimming-cutter, a jack for holding a last with its heel in engagement with the trimming-cutter, a pattern-plate adjustably mounted on the jack, means co-operating with the pattern-plate to regulate the operative position of the jack during the trimming operation, and a gage mounted on the jack and adapted to engage simultaneously corresponding parts of the last and the pattern-plate to assist in adjusting the plate.

12. A machine for trimming last-heels having, in combination, a trimming-cutter, a jack for holding a last with its heel in engagement with the trimming-cutter, the jack being pivotally mounted so that it may be angularly adjusted about an axis adjacent the point of operation of the cutter, and a heel-gage adapted to engage the lower angle of the heel of a last and locate it substantially at the pivotal axis of the jack.

13. A machine for trimming last-heels having, in combination, a trimming-cutter, a jack mounted to slide toward and from the trimming-cutter and provided with clamps adapted to swing laterally into engagement with a last on the jack, mechanism for actuating said clamps, said mechanism tending normally to move the clamps to operative position, and a manually-operable member mounted on the jack and adapted to move the jack toward and from the trimming-cutter, the manually-operable member being movable relatively to the jack and being connected with said mechanism so as to cause the clamps to be moved away from the last when the manually-operative member is operated to move the jack away from the trimming-cutter.

Corrections in Letters Patent No. 1,072,963.

It is hereby certified that in Letters Patent No. 1,072,963, granted September 9, 1913, upon the application of Henry F. Loewer, of Rochester, New York, for an improvement in "Machines for Trimming Last-Heels," errors appear in the printed specification requiring correction as follows: Page 3, line 58, for the word "stud" read *studs*; same page, line 125, and page 4, line 4, for the compound word "angle-gage" read *ankle-gage*; and that the said Letters Patent should be read with these corrections therein that the same may conform to the record of the case in the Patent Office.

Signed and sealed this 7th day of October, A. D., 1913.

[SEAL.]

R. T. FRAZIER,

Acting Commissioner of Patents.
